UNITED STATES PATENT OFFICE.

GEORGE McGOVERN, OF RICHMOND, VIRGINIA.

HAY OR COTTON PRESS.

SPECIFICATION forming part of Letters Patent No. 310,143, dated December 30, 1884.

Application filed December 5, 1884. (No model.)

To all whom it may concern:

Be it known that I, GEORGE McGOVERN, a citizen of the United States, residing at Richmond, in the county of Henrico and State of Virginia, have invented certain new and useful Improvements in Hay and Cotton Presses; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention has relation to baling-presses, and its object is to provide a simple, cheap, and at the same time powerful form of press for baling hay, cotton, and all sorts of balable material, and also for compressing the same 20 when required; and to these ends the novelty consists in the mechanical means or movement by which the same is accomplished, as will be hereinafter more fully described, and particularly pointed out in the claims.

25 In the accompanying drawings similar letters of reference indicate like parts of the invention.

Figure 1 is a perspective elevation of my improved press set up as a compress, and Fig. 30 2 is a similar view as an ordinary hand-power press for baling cotton, hay, and like material.

The frame of the press may be of any approved form, size, shape, or pattern to suit the objects in view, and I do not claim any 35 particular form of frame, as my invention is limited to the mechanical means for compressing the material.

A is the follower, and B B vertical screws journaled in the cross-beam C.

40 D is a wheel mounted loosely on the screw B, and provided with a key, b, fitting in the key-seat d in the screw B, so that when the wheel D is turned to the right or left the screw B will be raised or lowered while the 45 wheel retains its original position.

E is a worm-wheel, screw-threaded to receive the screw B, and F is a worm working in the teeth e on the periphery of said worm-wheel. From this construction it will be seen 50 that if the worm F be operated through the

medium of the shaft G and hand-wheel H the worm-wheel will be operated so as to force the screw B downward with an immense pressure without revolving the screw, and after the follower has been forced to its lowest point it 55 may be raised very rapidly by operating the wheel D, which rotates the screw without affecting the worm or worm-wheel.

In operation the follower is raised to its highest point and the press filled with hay or 60 cotton. The wheel D is then operated, which rapidly forces the follower down until the resistance of the material overcomes the power applied to said wheel, which is then abandoned, and the power applied to the shaft G. 65 This gives a slower motion to the follower, but is so greatly multiplied that an ordinary bale of cotton may be compressed into one-third of its original bulk, and when the invention is applied to a compress the hand-wheels are 70 removed and pulleys substituted, so that a steam-engine may be used.

In the case of the compress two or more screws may be used, and then the wheels D are 75 geared to a central pinion, K, which is provided on its upper face with a beveled gear, L, meshing with a similar gear, M, on a counter-shaft, N, provided with a belt or band pulley, O. This causes the two or more screws to 80 be operated simultaneously.

Having thus described my invention, what I claim as new and useful, and desire to secure by Letters Patent of the United States, is—

1. In a press, the combination, with the screw B, having key-seat d, worm-wheel E, 85 and worm F, of the wheel D, having key b, as and for the purpose set forth.

2. In a hay or cotton press, the horizontal shaft having worms F of wheels E, in combination with wheels D, loosely keyed to the 90 screw B, pinion K, and bevel-gear L, and the counter-shaft N, provided with bevel-gear M, as set forth.

In testimony whereof I affix my signature in presence of two witnesses.

GEORGE McGOVERN.

Witnesses:

E. H. BRADFORD,
H. J. ENNIS.
